DESIGN FOR A COMBINED MUFF AND HAND BAG

Rudolph Lobel, New York, N. Y.

Application August 30, 1935, Serial No. 58,369

Term of patent 3½ years

To all whom it may concern:

Be it known that I, Rudolph Lobel, a citizen of the United States and resident of New York city (Borough of Manhattan), in the county and State of New York, have invented a new, original, and ornamental Design for a Combined Muff and Handbag, of which the following is a specification, reference being had to the accompanying drawing, forming part thereof, of which Figure 1 is a view in side elevation; and Fig. 2 is a view in end elevation of a combined muff and handbag showing my new design.

I claim:

The ornamental design for a combined muff and handbag substantially as shown.

RUDOLPH LOBEL.
